his Attorney.

UNITED STATES PATENT OFFICE.

RICHARD HEINZ, OF NEW YORK, N. Y., ASSIGNOR TO AMERICAN LITHOGRAPHIC COMPANY, OF NEW YORK, N. Y., A CORPORATION OF NEW YORK.

FOLDING EASEL DISPLAY.

1,404,204.

Specification of Letters Patent. Patented Jan. 24, 1922.

Application filed September 21, 1920. Serial No. 411,745.

To all whom it may concern:

Be it known that I, RICHARD HEINZ, a citizen of the United States, and a resident of New York, borough of Queens, in the county of Queens and State of New York, have invented certain new and useful Improvements in Folding Easel Displays, of which the following is a specification.

This invention relates to folding easel displays and has for its object to provide a device of the character specified, or simple construction and efficient in operation.

To these ends and others which will be more particularly pointed out herein, my improvements comprise features illustrated in their preferred embodiment in the drawing accompanying this specification, where-in:

Figure 1 is a perspective view of the device erected for display. Fig. 2 is a perspective view of the device in partially collapsed condition. Fig. 3 is an enlarged edge view of the device in fully collapsed condition and looking in the direction of arrow 3 of Fig. 2, assuming the showing of said Fig. 2 to be wholly collapsed or folded. Fig. 4 is a fragmentary perspective view showing a modified form of the supporting member. The scale of Figs. 1, 2 and 4 is the same; the scale of Fig. 3 is about twice that of the other figures.

My improved display comprises display card 2 of any desired profile, having a folding score line 4 transversely or horizontally thereacross, preferably about midway its height, thus dividing said card or member into two articulated portions. Supporting member 5 is primarily of the usual vertically foldable design but characterized by having an upper ear 6^a secured to the upper portion 2^a of card 2, and a lower ear 6^b secured to the lower portion 2^b of said card, Fig. 4. If desired, ears 6^a and 6^b may be made continuous lengthwise, thereby forming one ear extending substantially the length of the supporting member and indicated in a general way by 6, Figs. 1 and 2. In this case those portions of the ear between score lines 9 and 11 are free and not secured to said card. Member 5 is also provided with wing 7 articulated to said ear and extending from score line 8. Said wing 7 may be set at right angles to ear 6 and card 2 for supporting said card as clearly shown in Fig. 1. Said member 5 may be provided with some

convenient means for locking it in its extended position, such as latch 14 of known character.

Said supporting member 5 is provided with three transverse and preferably parallel, equally spaced score lines 9, 10, 11, preferably normal to score line 8 and preferably located about midway the height of said member 5, and extending across both wing 7 and ear 6. Said score lines provide two intermediate members 12, 13, articulated to each other along line 10 and articulated to the upper and lower portions of the supporting member 5 along lines 9 and 11, respectively. This construction permits the outward folding of said members 12, 13 when wing 7 is folded flat against card 2, Fig. 2, whereby said card 2 may be folded along line 4 into substantially half the area occupied in its extended condition, Figs. 2 and 3. When the two sections 2^a, 2^b of card 2 are unfolded into one plane, members 12, 13 of supporting member 5 unfold into parallelism therewith, thereby permitting wing 7 to be opened out and locked into supporting position, Fig. 1.

I claim:

1. In a folding easel display the combination of a display member comprising two portions horizontally articulated, and a supporting member comprising an upper and a lower portion provided with two intermediate portions horizontally articulated to one another and to said upper and lower portions respectively, said upper and lower portions of the supporting member being vertically articulated respectively to the two display member portions.

2. In a folding easel display the combination of a display member comprising two portions horizontally articulated, a supporting member comprising an upper and a lower portion provided with two intermediate portions horizontally articulated to one another and to said upper and lower portions respectively, said upper and lower portions of the supporting member being vertically articulated respectively to the two display member portions, and means for locking said supporting member in a plane transverse the plane of said display member when in erected position.

3. In a folding easel display the combination of a display member comprising two portions horizontally articulated, and a sup-

porting member comprising an ear portion and a wing portion vertically articulated, said supporting member also comprising an upper and a lower portion provided with 5 two intermediate portions horizontally articulated to one another and to said upper and lower portions respectively, the ear portions of said upper and lower portions being fixed to the two portions of the supporting member of said display member respectively.

10. 4. In a folding easel display the combination of a display member comprising two portions horizontally articulated, a supporting member comprising an ear portion and a 15. wing portion vertically articulated, said

supporting member also comprising an upper and a lower portion provided with two intermediate portions horizontally articulated to one another and to said upper and lower portions respectively, the ear portions of said upper and lower portions being fixed to the two portions of the supporting member of said display member respectively, and means for locking said supporting member in a plane transverse the plane of said display member when in erected position.

20 25
In witness whereof, I hereby affix my signature, this 20th day of September, 1920.

RICHARD HEINZ.
